OF BAYONNE, NEW JERSEY, A CORPORATION OF NEW JERSEY.

APPARATUS FOR BURNING FINELY-DIVIDED FUEL.

1,086,714.

Specification of Letters Patent.

Patented Feb. 10, 1914.

Application filed September 22, 1911. Serial No. 650,742.

To all whom it may concern:

Be it known that I, DAVID J. IRISH, a citizen of the United States, residing at New York city, borough of Richmond, county 5 of Richmond, and State of New York, have invented certain new and useful Improvements in Apparatus for Burning Finely-Divided Fuel, of which the following is a specification.

10 I have found that by admitting air for combustion at various points to a stream or jet of finely-divided fuel the form of the flame resulting therefrom may be materially varied, said variation following a definite 15 law. Thus, if the points at which air is admitted are confined to the sides of a stream or jet of fuel circular in cross section, the resulting flame will be narrowed in width and correspondingly increased in height. On 20 the other hand, if the air is admitted only above and below a stream of fuel circular in cross section, the resulting flame will be broadened and reduced in height.

Many instances occur in practice where 25 burners or sprayers for finely-divided fuel, which produce a conical stream of fuel of circular section, are used in furnaces of limited proportions; that is, the furnace may be limited in height but have plenty of width, 30 or vice versa. My invention is designed to adapt these so-called "round flame burners" to the special furnace conditions wherein a broad flattened flame is desired. It is not necessary to entirely dispense with air admission at certain points but air may be admitted entirely around the burner and, if it be properly proportioned in amount in accordance with the above theorem, the corresponding effect will be produced on the 35 form of the flame.

40 My invention will be understood by reference to the accompanying drawings in which—

Figure 1 is a longitudinal section through 45 a boiler furnace showing the application of the invention thereto; Fig. 2 a front elevation of the boiler of Fig. 1 showing the application of two burners to the furnace; Figs. 3 and 4 front views of forms of plates 50 through which the air for combustion may be admitted to control the form of the flame in accordance with the present invention; Fig. 5 a vertical section on the plane of the line 5—5 of Fig. 6 showing another form of 55 plate; Fig. 6 a horizontal section on the

plane of the line 6—6 of Fig. 5; and Figs. 6 7, 8 and 9 are diagrammatic views showing the effect of air distribution on the flame.

Similar reference numerals indicate similar parts in the several views.

60 For the purpose of illustration I have shown my invention applied to a boiler furnace of limited head room and great width. The use of a burner in this form of furnace giving a conical flame circular in section is 65 objectionable for the reason that the flame comes into interference with the floor of the furnace and the water-heating surfaces forming the upper portion thereof, particularly at the entrance. With this form of 70 furnace it is desired to spread the flame from the burners across the furnace in the direction of its width without using an excessive number of burners, or burners which in themselves produce a broad flat flame. In 75 carrying out my invention any suitable form of burner 1 may be used which will properly project a finely-divided fuel such as gas, oil or solid fuel in the form of a substantially conical flame, into the combustion 80 chamber 2.

85 In order to flatten the flame, which would ordinarily be produced by the burner, I admit the air for combustion through an opening which will permit the entrance of a 90 larger volume above and below the flame than is admitted at the sides. This can be conveniently accomplished by setting a box or frame 3 having an oblong or oval opening into the furnace wall, the burner 1 terminating in proximity to such opening, as shown in Figs. 1 and 6, and substantially coincident with the axis thereof. In accordance with the principles above stated 95 the volume of air admitted above and below the flame is greater than at the sides and this has the effect of pressing upon the upper and lower sides of the flame and flattening it horizontally.

100 In Fig. 7 I have shown diagrammatically the effect of admitting air for combustion through a circular opening 4, equal in volume at all points around the burner. In such case the flame will spread out in a conical form, circular in section, as indicated by the arrows. With the major axis 105 of the air opening vertical, as shown diagrammatically in Fig. 9, the flame will be flattened as indicated by the arrows; that is, with its major axis horizontal.

If the air opening is so placed that its major axis is horizontal, as shown in Fig. 8, then the flame will be narrowed horizontally and increased in height, as indicated by the arrows, that is the flame will be of oval shape with its major axis vertical. As shown by Figs. 8 and 9, the major axis of the flame will be practically at right-angles to the major axis of the opening for air admission.

If it is desired to give to the air for combustion a whirling or rotating motion, I place within the opening a series of blades inclined at an angle to the plane of the opening and spaced apart to provide apertures for the admission of air. A convenient way of doing this is to make the blades in the form of a plate, either a casting or blades of sheet metal secured to a suitable base. In Fig. 3 the blades 5 are secured at their inner ends to a central ring to provide an opening through which the fuel may be projected, and at their outer ends to an oblong frame or plate 6. By using such a device, the flame is not only flattened by reason of the oblong form of the air opening, but the air for combustion is deflected from its normal direction of travel and given a whirling or rotating motion by which is secured a continuous, uniform and intimate mixture, making thereby a solid flame.

Instead of an oblong plate, I may fill an oval opening in a plate 7 with blades 8 inclined to the plane of the plate, as shown in Fig. 4, to deflect the air and to give it a whirling or rotating motion. In this case, as with an oblong or oval opening without the blades, the greater volume of air admitted at one point than another produces a flattened flame.

In Figs. 5 and 6 I have shown a box 9 rectangular in vertical section which may be set into the furnace casing and which has at the furnace end thereof a grating of vertical blades 10 inclined to the plane of their supports so as to deflect the air without giving it a whirling motion. All of these forms of openings, in which the area for air admission is longer in one direction than the other, produce substantially the same flattening effect on the flame. The major axis of such opening may be vertical or horizontal, or any other position, to produce the flattening in the desired direction.

To still more fully explain my invention, I will describe a specific example of practising it employing a box having a rectangular opening 8 inches by 4 inches, with the major axis vertical as shown in Fig. 9, and without an air deflecting plate. The burner was of the construction shown in Peabody Patent No. 1,007,793, dated November 7, 1911, with an outlet orifice three sixtieths of an inch in diameter. The pres-

sure on the oil was about 200 pounds and the oil was what is commercially known as "Texas Crude" of 27 B. The temperature of the oil entering the burner was about 180 degrees Fahrenheit. A natural draft was employed of about .2 of an inch in the furnace. The furnace was about 8 feet wide, 32 inches high at the front and about 7 feet at the rear and 7 feet long. There was about 190 pounds pressure in the boiler which was of the type shown in Fig. 1 with the grate bars removed. The following observations were made: Ignition began in a plane about 12" to 14" behind the box, and about 13 to 15 inches from the front of the burner. The flame extended substantially the length of the furnace, and was substantially oval in cross-section with the major axis horizontal, and at its further end the horizontal axis was about 60 inches, and the minor or vertical axis was about 24 inches. Upon placing the air-inlet box as shown in Fig. 8, that is, with the major axis of the opening horizontal, the conditions observed were practically the same as above stated except that the major axis of the flame was vertical instead of horizontal. Upon placing an air deflecting plate, of the form described in Fig. 3, in the rectangular opening, the same flattening of the flame was observed, and in addition the air for combustion was given a whirling or rotating motion, at which time the following observations were made: Ignition began in a plane about 1½ to 2 inches behind the box, and about 2½ to 3 inches behind the burner. The flame extended into the furnace a distance of from four to five feet back of the box, and was substantially oval in cross-section with the major axis horizontal, and at its further end the minor or vertical axis was about 20 inches. The above differences in position and size of flame is due to the thorough intermixing of the air and oil carried by the placing of an air deflecting plate, of the form described in Fig. 3, in the rectangular opening. Upon removing the box and admitting air through a circular opening in the furnace wall, as shown in Fig. 7, the flame was substantially circular in cross-section. From these observations it therefore appears that the admission of a greater quantity or volume of air above and below the burner than at the sides produces a broad flattened flame. By reversing these conditions, that is, admitting a greater quantity or volume of air at the sides than above or below the burner produces a broad flattened flame with the major axis vertical. What I claim and desire to secure by Letters Patent of the United States is:—

1. In combination, a combustion chamber, a burner for finely divided fuel, a casing having an opening for the admission of air for combustion, said opening being longer in one direction than the other, and means

to give to the air a whirling or rotating motion as it enters the combustion chamber.

2. The combination with a burner, of an air deflecting device comprising a plate having an opening longer in one direction than the other, a plurality of inclined blades spaced apart to provide apertures for the admission of air and secured at their outer ends to said plate, a support for the inner 10 ends of the blades said inner support hav-

ing a central opening, and the burner terminating in proximity to said central opening.

In testimony whereof I have hereunto signed my name in the presence of two subscribing witnesses.

DAVID J. IRISH.
